UNITED STATES PATENT OFFICE.

ADNAH McMURTRIE, OF NEW YORK, N. Y., ASSIGNOR TO THOMAS & BETTS,
OF NEW YORK, N. Y., A FIRM COMPOSED OF ROBERT MCK. THOMAS AND
HOBART D. BETTS.

DESIGN FOR A NIPPLE.

SPECIFICATION forming part of Design No. 35,516, dated December 31, 1901.

Application filed October 15, 1901. Serial No. 78,755. Term of patent 14 years.

To all whom it may concern:

Be it known that I, ADNAH McMURTRIE, residing at New York, in the county and State of New York, have invented and produced a new and original Design for a Nipple for Electrical Conduits, of which the following is a specification.

The drawings show in Figure 1, in side elevation, a nipple in which my novel design is embodied. Fig. 2 is a vertical section of the same, and Fig. 3 a plan view.

The novelty of my design resides in the contour of the periphery, the reference-letter *a* designating a base of annular form, and *b* designates a polygonal body, the facets whereof extend from the base to the mouth *c*. Inte-

riorly the nipple has a threaded bore *d*, separated by an annular constriction *e* from a flaring mouth *f*.

Having thus described my design, what I claim, and desire to secure by Letters Patent, is—

The design for a nipple for electrical conduits, substantially as herein shown and described.

In testimony whereof I have signed my name to this specification in the presence of two subscribing witnesses.

ADNAH McMURTRIE.
